Be it known that I, Isaac Desjouche, of the City and County of St. Louis and State of Missouri, have invented or produced a new and original Design for the Plates of a Parlor Book and Heating Store; and I do hereby declare that the following is a full and exact description of the same, reference being had to the accompanying drawings and to the letters of reference marked thereon, making a part of this specification, in which Fig. 1 represents the front plate, ornamented in the sunk panels A.
